UNITED STATES PATENT OFFICE.

JAY BRIGGS, OF LOS ANGELES, CALIFORNIA, ASSIGNOR OF ONE-HALF TO W. T. GUNN,
OF SAN DIEGO, CALIFORNIA.

AUTOMATIC ELECTRIC CROSSING-GATE.

1,134,584.

Specification of Letters Patent.

Patented Apr. 6, 1915.

Application filed April 15, 1914. Serial No. 831,986.

To all whom it may concern:

Be it known that I, JAY BRIGGS, a citizen of the United States, residing at Los Angeles, in the county of Los Angeles and State 5 of California, have invented a new and useful Automatic Electric Crossing-Gate, of which the following is a specification.

This invention relates to crossing gates, which are adapted to be located at railway 10 crossings, and to be automatically operated electrically to close the gates during the passing of a train in either direction, and to raise the gates after the train has passed.

The invention is capable of being used on 15 railways having one or more tracks, and the object is to provide a mechanism of compact arrangement simple in construction and effective and durable in use.

Referring to the drawings: Figure 1 is a 20 diagrammatical view showing the electrical connections. Fig. 2 is a plan view showing the device as applied to a single track railway. Fig. 3 is a plan view showing the device as applied to a double track railway. 25 Fig. 4 is a plan view showing the device as applied to a four track railway. Fig. 5 is a cross section on line x^5-x^5 , Fig. 2. Fig. 6 is a cross section on line x^6-x^6 , Fig. 3. Fig. 7 is a cross section on line x^7-x^7 , Fig. 30 4. Fig. 8 is an enlarged section similar to Fig. 6. Fig. 9 is a sectional view on the line x^9-x^9 of Fig. 8.

1 and 2 designate track portions which are adjacent to a crossing track portion 3.

35 4 designates the crossing. The track sections 1 and 2 are insulated from the crossing section 3.

5 designates a gate which is operated into either a horizontal or vertical position by a 40 gear 6, which is in turn operated by a pinion 7, which rotates with a gear 8, the gear 8 being rotated by a pinion 9 driven by a reversible motor 10.

The starting and stopping of the motor is 45 controlled by a switch designated in general 11, which consists of two pivoted levers 12 and 13 connected by a rod 14 carrying a switch blade 15 adapted to make connection between contacts 16 and 17 or between contacts 18 and 19, and a roller 20 carried on the gear 6 is adapted to move against either of the levers 12 or 13 to shift the blade 15 when the gate 5 has arrived in either vertical or horizontal position.

55 21 designates a reversing switch which

comprises a solenoid 22 with armature 23 carrying a switch blade 24 and adapted to place terminals 25 and 26 in connection with each other or to place terminals 27 and 28 in connection with each other. Wires 29 60 and 30 lead from the terminals 27 and 25 to the motor 10. A branch wire 31 leads from wire 30 to terminal 17, and a branch wire 32 leads from wire 29 to terminal 18. A wire 33 leads from the motor 10 to a 65 source of electric energy 34, said wire 33 being also connected to contacts 16 and 19 aforesaid and a wire 35 leads from the motor 10 to a contact 36, which forms part of a main switch designated generally 37, 70 and having also contacts 38, 39, 40, 41, 42, 43, and 44. A wire 45 extends between the contacts 26 and 28, and a wire 46 extends from wire 45 to wire 35. A wire 47 leads from one pole of the solenoid 22 to the wire 75 33, and a wire 48 leads from the other pole of the solenoid 22 to the contact 40. The main switch 37 has two solenoids 49 and 50, the armatures of which are connected to a pivoted lever 51, the latter having 80 blades 52 and 53 on its opposite ends, blade 52 being adapted to connect contacts 41 and 52 or to connect contacts 43 and 44, while blade 53 is adapted to connect contacts 38 and 39 or contacts 36 and 40. A rigid arm 85 53' extends from the lever 51, and has a blade 54 adapted to open or close a circuit through contacts 55 and 56, and also has a rigid arm 57 with a roller 58, which is arranged between two spring pressed plungers 90 59 and 60, the respective plungers having detents 61 and 62 and having switch blades 63 and 64, the switch blade 63 being adapted to connect contacts 65 and 66, and a switch blade 64 being adapted to connect contacts 95 67 and 68. Springs 69 on opposite sides of the arm 53 tend to hold the lever 51 in central position.

Solenoids 70 and 71 have armatures 72 and 73 respectively, the armature 72 being 100 adapted to engage detent 62 and hold the blade 64 in connection with contacts 67 and 68, while armature 73 is adapted to engage detent 61 and hold blade 63 in connection with contacts 65 and 66. The armature 72 105 carries a blade 74 which is adapted to connect contacts 75 and 76, and the armature 73 has a blade 77, which is adapted to connect contacts 78 and 79. Springs 72' and 73' 110 serve to elevate the armatures 72 and 73.

One pole of solenoid 70 is connected by wire 81' with contact 67, and the other pole is connected by wire 82' with contact 76. One pole of solenoid 71 is connected by wire 83 with contact 65 and the other pole is connected by wire 84' with contact 78. A wire 79 leads from contact 75 to contact 38, and the wire 80 leads from contact 76 to one rail of track section 2. A wire 81 leads from the other rail of track section 2 to the corresponding rail of track section 1, and a wire 82 leads from the wire 81 to contact 55. A wire 83 leads from wire 81 to the source of energy 34. A wire 84 connects the corresponding poles of solenoids 49 and 50, and a wire 85 connects the other pole of solenoid 49 with contact 44. A wire 86 connects the other pole of solenoid 50 with contact 39. A wire 87 connects one pole of solenoid 49 with contact 42, and a wire 88 leads from contact 42 to contact 36. A wire 89 connects contacts 40 and 41. A wire 90 connects contact 43 with contact 79. A wire 91 leads from one rail of track section 1 to contact 78, and a double pole switch 92 is arranged in wires 90 and 91. A wire 93 connects contacts 66 and 68, and a wire 94 connects contact 66 with wire 33. A wire 95 connects contact 56 with wire 88.

Assuming the gate 5 to be in vertical position, when a train passes onto the track section 1, it closes the circuit between the two rails of that track section and through the associated wires 81 and 91, whereupon a circuit is established as follows: through wire 91 to contact 78, through switch blade 77 to contact 79, through wire 90 to contact 43, through blade 52 to contact 44, through wire 85 to solenoid 49, through wire 87 to contact 42, through wire 88 to contact 36, through wire 35, through the field of motor 10, then through wire 33 to battery 34, through wire 83 to wire 81 and to track section 1 and wheels and axle of car to opposite track rail and wire 91, thus completing the circuit through solenoid 49. Solenoid 49 being thereby energized pulls down lever 51, still keeping blade 52 in connection with contacts 43 and 44 to maintain the foregoing circuit, and moving blade 53 into connection with contacts 40 and 36. When blade 53 connects contacts 36 and 40 a branch circuit from the foregoing circuit is established from wire 87, contact 42, wire 88, contact 36 to wire 35 and motor, also through blade 53 to contact 40, through wire 48, through solenoid 22 through wire 47 to wire 33 in the foregoing circuit, thereby energizing solenoid 22 which lifts blade 24 to connect contacts 27 and 28, thereby closing the circuit through wire 29 and through the armature of the motor, and through wire 30 to wire 31, contact 17, blade 15, contact 16, and wire 33 to the battery. The motor then revolves and through the beforede-

scribed gearing lowers the gate 5 into a horizontal position, at which time the roller 20 strikes the lever 12 and shifts the blade 15 away from contacts 16 and 17 into connection with contacts 18 and 19, which opens the armature circuit and stops the gate. Although at this time the blade 15 connects contacts 18 and 19 and thus connects wire 32 with wire 30 no current flows through wire 30 because blade 24 is above contacts 25 and 26. The motor thus remains stationary with the gate lowered while the train passes. As soon as the front wheels of the train pass onto track section 2, they connect wires 80 and 81 so that a circuit is formed from wire 80 to contact 76, through wire 82, solenoid 70, contact 67, and through blade 64, which, it will be remembered, had been previously moved to the left, through contact 68 and wire 93 to contact 66, through wire 94 and wire 33 to battery 34, wire 83 to wire 81 and track section 2, completing this circuit, and as solenoid 70 is thus energized, it moves the armature 72 down into engagement with detent 62, which is already standing in position at the left to be engaged, which locks the plunger 60 in its position at the left and maintains the circuit through blade 64 between contacts 67 and 68. This movement of armature or core 72 also interrupts the connection between contacts 76 and 75 through switch blade 74. When the last wheels of the train pass off from track section 1, it breaks the first described circuit through the solenoid 49, which has been maintained until that time, the circuit being broken between wires 81 and 91 as soon as the wheels pass off from rails of track section 1, whereupon the springs 69 restore lever 51 to central position. Plunger 60 being still held in position at the left by operation of the core of solenoid 70, holds the circuit of solenoid 50 open even after the switch lever 51 has returned to normal position and closes connection at 53. This prevents the energization of solenoid 50 by the passage of the train onto the second section. If it were not for the holding open of the contact 74 by the solenoid 70 at this time the passing of the train onto the second section would operate the solenoid 50 as soon as the switch lever 51 returns to normal position and it is to prevent this and the consequent lowering of the gate by operation of the second section that the contact 74 is opened by the solenoid 70 and said solenoid holds its contact in open position as long as current is supplied to said solenoid from the wires leading to the second section, by reason of the presence of a train on said second section.

When the circuit is broken between contacts 40 and 36 by movement of switch lever 51 to normal position it breaks the circuit between wires 35 and 48, and thereby breaks

the circuit through solenoid 22, and the armature thereof then drops by gravity so that blade 24 connects contacts 25 and 26. The armature 72 of solenoid 70 continues to hold the detent 62 and plunger 60 to the left. With blade 15 already connecting contacts 18 and 19 and blade 24 now connecting contacts 25 and 26, circuit is formed from wire 35 through wire 46 through contact 26, blade 24, contact 25, wire 30, armature of motor, wire 29, wire 32, contact 18, blade 15, contact 19, and wire 33 to battery, and the motor 10 is caused to revolve in the opposite direction to raise the gate 5 to vertical position, and as soon as a vertical position of the gate is reached the roller 20 has been moved back to the right against lever 13 and swings the blade 15 out of engagement with contacts 18 and 19, thereby stopping the motor and holding the gate vertical. As soon as the last wheels have left the rails 1 and the circuit is broken between wires 81 and 91, and the main switch resumes normal central position, current is supplied from wire 82 to contact 55, blade 54, contact 56 and wire 95 to wire 88 and contact 36 and to the motor through the before described connections. If a train comes in the opposite direction, and it reaches track section 2, it closes the circuit between wires 80 and 81, and a circuit is established as follows: through wire 80 to contact 76, through blade 74 and contact 75, through wire 79 to contact 38, through blade 53 and contact 39, through wire 86 and solenoid 50, through wire 84 to wire 87, to contact 42, through wire 88 to contact 36, through wire 35 to the field of motor 10, and then through wire 33 to battery 34, through wire 83 and wire 81 to track section 2, thereby energizing solenoid 50 and acting upon lever 51 to move down blade 53 on contacts 38 and 39 and lift blade 52 onto contacts 41 and 42 and move spring pressed plunger 59 to the right. When the blade 52 connects with contacts 41 and 42, a circuit is also established from solenoid 50, through wire 84 to wire 87 to contact 42, through blade 52 to contact 41, wire 89 to contact 40, wire 48 to solenoid 22, through wire 47 to wire 33, battery 34, wire 83, wire 81, through the track section 2, wire 80, contact 76, blade 74, contact 75, wire 79, contact 38, blade 53, contact 39, wire 86 to solenoid 50, which energizes solenoid 22 and lifts armature 24 and makes connection between contacts 28 and 27, thereby closing the circuit through wire 29 and through the armature of the motor, and through wire 30 to wire 31, contact 17, blade 15, contact 16, wire 96, and wire 33 to battery. The motor then revolves through the before described gearing and lowers the gate 5 into a horizontal position, at which time the roller 20 strikes the lever 12 and shifts blade 15 away from contacts 16 and 17 into connection with contacts 18 and 19, which opens the armature circuit and stops the motor with gate lowered. As soon as the train passes onto track section 1, it closes the circuit between wires 91 and 81, so that a circuit is formed from wire 91 through wire 84, solenoid 71, wire 83, contact 65, blade 63 which, it will be remembered, had been previously moved to the right, through contact 66 and wire 94, to wire 83, to battery 34, wire 83, to wire 81, and track section 1, and as solenoid 71 is thus energized it moves the armature 73 into engagement with detent 61 which locks the plunger 59 in its position at the right. When the last car passes off from track section 2, it breaks the circuit through solenoid 50, which had been maintained until that time, the circuit being broken between wires 80 and 81 as soon as the wheels pass off from the rails of track section 2, whereupon the spring 69 restores lever 51 to central position, which breaks the circuit through solenoid 22 between contacts 42 and 41, and its armature blade 24 drops to contacts 25 and 26, whereupon the motor is revolved in the opposite direction to raise the gate 5 into the vertical position, at the completion of which movement the roller 20 strikes arm 13 and moves blade 15 out of connection with contacts 18 and 19 and stops the motor with the gate in raised position. Solenoids 22, 70, 71, 49, and 50, together with their associated switches are located in a box 96, which is inclosed in a case 97, as shown in Fig. 8, and located also in the case 97 is the motor 10 and gearing, through which it operates the gates associated therewith. As shown in Fig. 8, the unit is constructed for a double track road, and 98 is a shaft upon which is mounted the gear 8, before referred to, which is driven by the motor pinion 9. The gate 5 is rigidly secured to the shaft 98. Another case 97' is located on the opposite side of the track and contains a similar mechanism to that contained in the case 97. Journaled in the case 97 is a short shaft 99, which carries a gate 5^a. The gate 5^a is not controlled by the operating mechanism of box 97, but by the mechanism in the opposite box 97' by means of any suitable connection. As herein shown, the connection comprises a sprocket 100 on shaft 99 which is connected by chain 101 with a sprocket 102 on a tubular shaft 103 which is located in the ground below the track and extends to the other side of the track. Within the tubular shaft 103 is a solid shaft 104 having a sprocket 105 which is connected by a chain 106 with a sprocket 107 on shaft 98. The other end of the tubular shaft 103 has a sprocket 102' which is connected by a chain 106' with a sprocket 107' on shaft 98', shaft 98' being operated by gears 8', 9', and motor 10', and carries a gate 5^b. Also mounted on box 97' is a shaft 99' which carries gate 5^c, and has a

sprocket 100' which is connected by a chain 101' with a sprocket 105' on the solid shaft 104. Thus, motor 10 operates gates 5 and 5^c, while motor 10' operates gates 5^a and 5^b.
5 By this means on a double track road gates are lowered on both sides of tracks, motor 10 being operated by a train on one track, and motor 10' being operated by trains on the other track. Where the apparatus is
10 used on a single track, as in Fig. 2, the box 97^a contains mechanism for operating the gate 5 and the shaft 104^a, which is driven in a manner as shown in Fig. 9, extends across under the track and operates gate 5^c, in this
15 instance box 97^b containing only the sprocket and each connection from gate 5^c to the shaft 104^a.

Fig. 3 is a diagrammatical plan view of the mechanism shown in detail in Fig. 8.
20 Fig. 4 is a diagrammatical plan view of the apparatus as applied to a four track road, in which case two sets of mechanism similar to Fig. 8, are employed, each being independent of the other and each motor being connected with its individual track, so that a train running on any one track will operate the motor connected therewith, and that motor will lower and raise a gate on each side of the track.

30 What I claim is:

1. In combination, a gate, a motor for operating the gate, a battery, a circuit through the armature of the motor, a circuit through the field of the motor, the field circuit being connected with separate track sections and adapted to be closed by a train on a track section, said battery being in the field circuit, a pole changing switch in the armature circuit, a solenoid for operating the pole changing switch, one pole of the solenoid being connected with the battery and the other pole being adapted to be connected with either of the track sections, a main switch means connected with the battery and with both track sections for connecting the solenoid of the pole changing switch with either of the track sections.

2. In combination, a gate, a motor for operating the gate, a battery, a circuit through the armature of the motor, a circuit through the field of the motor, the field circuit being connected with separate track sections and adapted to be closed by a train on a track section, said battery being in the field circuit, 50 a pole changing switch in the armature circuit, a solenoid for operating the pole changing switch, one pole of the solenoid being connected with the battery and the other pole being adapted to be connected with either of the track sections, a main switch means connected with the battery and with

and with both track sections for connecting the solenoid of the pole changing switch with either of the track sections, and means operated by the motor and acting in conjunction with the pole changing switch for breaking the armature circuit when the gate is moved into erect or horizontal position.

3. In combination, a gate, a motor for operating the gate, a battery, a circuit through the armature of the motor, a circuit through the field of the motor, the field circuit being connected with separate track sections and adapted to be closed by a train on a track section, said battery being in the field circuit, 65 a pole changing switch in the armature circuit, a solenoid for operating the pole changing switch, one pole of the solenoid being connected with the battery and the other pole being adapted to be connected with either of the track sections, a main switch means connected with the battery and with both track sections for connecting the solenoid of the pole changing switch with either of the track sections, and means for maintaining the armature circuit through one of the track sections after the main switch means has been actuated by the train passing on to the adjacent track section.

4. In combination with two track sections 70 and a crossing section, gates, means operated by a train passing onto either of said track sections for operating the gate to lower the same and for raising the gate when the train passes off of said section, and means operated by such train as it enters the second section in passing the crossing for preventing the operation of the gate by the gate operating means controlled by said second section.

5. In combination with a crossing and two track sections at opposite sides thereof, a gate operating motor, a motor operating circuit including means controlled by the passing of a train onto the first of either of said sections in passing the crossing for operating the motor to lower the gate and means operated by passing of the train off of said first section for operating the motor to raise the gate, and means controlled by the passing of such train onto the second section as it passes the crossing to prevent operation of the motor operating circuit by said second section.

In testimony whereof, I have hereunto set 115 my hand at Los Angeles, California, this 10th day of April, 1914.

JAY BRIGGS.
